UNITED STATES PATENT OFFICE.

HENRY A. WISE WOOD, OF NEW YORK, N. Y., AND CONRAD NORDFORS, OF JERSEY CITY HEIGHTS, NEW JERSEY, ASSIGNEES TO WOOD NEWSPAPER MACHINERY CORPORATION, OF NEW YORK, N. Y., A CORPORATION OF VIRGINIA.

FOLDING DELIVERY MECHANISM.

1,419,188.

Specification of Letters Patent. Patented June 13, 1922.

Application filed February 2, 1915, Serial No. 5,641. Renewed October 14, 1921. Serial No. 507,751.

To all whom it may concern:

Be it known that we, HENRY A. WISE Wood and CONRAD NORDFORS, citizens of the United States, said Wood residing at New 5 York, in the county of New York and State of New York, said Nordfors residing at Jersey City Heights, county of Hudson, and State of New Jersey, have invented a new and useful Folding Delivery Mechanism, of 10 which the following is a specification.

This invention relates to that class of folding mechanism in which the fold of the sheet is tucked into a set of oscillatable gripping jaws and these jaws are caused to turn 15 for the purpose of drawing the fold of the sheet inwardly, thoroughly creasing it, and firmly holding it and then ejecting the sheet and delivering it.

The principal objects of this invention are 20 to provide a folding delivery mechanism of this type capable of operating at a very high speed without any unnecessary strain on the web and without excessive vibration and noise; to provide for folding a sheet in 25 this way so as to prevent bending the body of the folded sheet away from the fold line on which it is held by the jaws in such a way as to tend to fold back the sheet under the body; and to provide an improved form of 30 carrier and other features of construction as will appear hereinafter.

Reference is to be had to the accompanying drawings, in which—

Fig. 1 is a side elevation of a part of a 35 web press frame showing a preferred embodiment of this invention applied thereto;

Fig. 2 is a detail side view of a feature thereof with parts shown in section;

Fig. 3 is a sectional view of the gripping 40 jaws on the line 3—3 of Fig. 4;

Fig. 4 is an end elevation of the frame showing the same construction;

Figs. 5, 6 and 7 are side views showing 45 the positions of the gripping jaws and other parts at three different stages in the rotation of the carrier, details of construction being omitted, and

Fig. 8 is a diagrammatic view indicating 50 the relative positions of the jaws or the arm which operates them at different parts of the rotation of the carrier.

The folding cylinder 10 is shown as provided as usual with paper pin points and cutting rubbers or cheeks and with two stationary tucker blades 11 fastened thereto.

An ordinary cutting cylinder 12 is shown having, of course, the usual knife. This drawing shows only one half of a double folder but it will be understood that the other half can be arranged in a similar way as is 60 well understood in this art.

A rotary carrier or delivery member is located vertically below the folding cylinder 10 and having a pair of discs 13 which constitute the supporting part of it. These discs 65 are carried by a shaft 30 which is journalled on the frame A of the folder. These two discs carry capped bearings 15 in which are journalled a pair of opposite rollers 14 each one constituting a set of gripping jaws. 70 These rollers are provided with gears or pinions 16 on their rear ends adapted to mesh with similar gears or pinions on another pair of rollers 17 constituting exactly similar jaws. These rollers 17, however, are 75 provided with studs 18 which are supported in brackets 19. By means of springs 20 carried by said brackets on the frame and held by nuts 21 the necessary tension is provided for pressing the rollers 17 against the 80 rollers 14. The front ends of the rollers 14 are provided with lever-crank 22 which are connected with two eccentric straps 23. An eccentric 24 is provided on the shaft 30 at the front and the hub of this eccentric which 85 surrounds the shaft passes through the frame A. One eccentric, operates two straps 23 and the single hub which extends through the side of the frame A can be turned on its own axis for adjusting this eccentric while the 90 machine is running if desired in order to take care of paper of different weights of thicknesses. In order to provide a convenient adjustment for this purpose the hub of the eccentric is provided with a worm-wheel 95

26 on the outside of the frame which meshes with a worm 27 journalled in a bracket 28. This worm is mounted on a square ended shaft 29 so that the operator can perform the adjustment while the machine is running by turning this worm in the desired direction.

The rear end of the shaft 30 carries two gears 32 and 33. The gear 32 meshes with a gear 34 fastened to the shaft of a bending roller 35. This roller is journalled in brackets 36 on the side frames of the folder and operates at web speed. The gear 33 is a part of the ordinary driving train for the folding mechanism.

The carrier itself is made up, in addition to the discs 13, of a set of circular supports 37 securely fastened to the shaft 30 and spaced apart therealong. These discs serve 5 for supporting the sheet as it passes around with the carrier. They are circular, but have a depression for receiving each pair of rollers 14 and 17.

At the bottom, delivery belts 38 are shown 10 for receiving the folded sheet from the carrier. A shaft 39 at this point is provided with a set of strippers 40 which enter grooves 41 in the rollers 14 and 17 which grooves separate these rollers into the plurality of 15 jaws mentioned. These strippers are shown as provided with adjustable stops 42 clamped to the strippers by means of clamping screws 43 operating in elongated slots with which the strippers are provided. The 20 delivery belts 38 can be driven in any desired way preferably from the shaft 30 but this drive is not illustrated.

The operation of the device will be most 25 obvious from a consideration of the figures on the last sheet of drawings. The eccentric 24 is so positioned that from the position shown in Fig. 5 to that shown in Fig. 6 the tendency of the folding rollers or gripping 30 jaws 14 and 17 is to pull toward the center of the carrier, a sheet which has been tucked 35 between them by the blade 11. At this time one leaf of the sheet may rest on the carrier while the other passes over the bending roller 35 which, as has been stated, is driven 40 at web speed. From the position shown in Fig. 6 to that shown in Fig. 7, the motion of the gripping jaws or rollers is reversed, and the sheet is gradually ejected from the grip 45 of the rollers so that it can be stripped by the strippers and dropped on the delivery belts. The operation of ejecting consists simply in moving the fold of the sheet outwardly in a radial direction until the jaws loose their grip on it. All the way around from the point 50 shown in Fig. 7 to that shown in Fig. 5 the rollers retain a substantially open position ready to receive a sheet, but this is the idle part of the rotation.

In this way it will be seen that the sheet is 55 tucked into the jaws in the position shown in Fig. 5, and then as the carrier rotates through a quarter it is constantly and gradually pulled in toward the center of the carrier, the sheet thus having a speed slightly 60 greater than web speed. At this point it will be seen that the shape of the folding rollers is such as to prevent any sharp bend in the sheet as it is carried from the position shown in Fig. 5 to that shown in Fig. 6. 65 This is accomplished by making these rollers or jaws cylindrical and concentric with their shafts or axes of oscillation on their inner and gripping portions and by flattening them out slightly in the outside. They are 70 still left curved however on the outside and

a gradual curvature provided at the point where the two curves meet. This also prevents these rollers from projecting out materially beyond the circumference of the carrier and interfering with the folding cylinder as 70 they pass it, but as they do project slightly this cylinder is provided with a concave surface to permit them to pass.

Fig. 8 indicates the positions of the arms 75 22 at different points in the circumference of the carrier.

Although we have illustrated and described only one form of the invention, we are aware of the fact that it is capable of being carried out in many other ways without departing from the scope thereof as expressed in the claims. Therefore we do not wish to be limited to the details of construction described herein, but what we do claim is:—

1. In a folding delivery mechanism, the combination with a folding cylinder having a tucker blade, of a rotary carrier, and a pair of rollers on the carrier for receiving sheets from the folding cylinder and gripping 90 them at the fold, said rollers being turned on parallel axes, and each having a gripping surface which constitutes part of a modified cylinder having the center of oscillation as its central axis and flattened on the outer 95 side.

2. In a folding delivery mechanism, the combination with a folding cylinder having a tucker blade, of a rotary carrier having means for receiving sheets from the folding 100 cylinder, gripping them at the fold and continuously drawing the fold inward toward the center of the carrier as the carrier rotates through a material part of a revolution and for then commencing to eject the fold from 105 the gripping means, said receiving and gripping means comprising a pair of members mounted on the carrier and adapted to oscillate on parallel axes, each having a gripping surface which constitutes part of a cylinder 110 and flattened on the outer side, a set of stripping fingers for removing the folded sheets from the carrier, said gripping members having slots for receiving said stripping fingers dividing the gripping members 115 into a series of jaws.

3. The combination of a rotary carrier for a folding mechanism, a shaft on which said carrier is mounted, a pair of sets of oscillatable jaws mounted on said carrier, an eccentric loose on said shaft, an eccentric strap carried by the carrier, and means operated by said eccentric and strap for oscillating said jaws inwardly at their points of contact during a material part of a revolution of 120 the carrier after a sheet has been gripped by the jaws, and for thereafter oscillating the jaws in the opposite direction to eject the folded sheet.

4. A rotary carrier for a folding mecha- 130

nism having means for receiving sheets from a folding cylinder, gripping them at the fold and drawing the fold inward toward the center of the carrier as the carrier rotates through a material part of a revolution, and means whereby the amount of motion toward the center of the carrier can be adjusted while the carrier is rotating.

5. The combination of a rotary carrier, a pair of sets of oscillatable jaws mounted on said carrier, a non-rotatable but circumferentially adjustable eccentric, an eccentric strap carried by the carrier, means operated by said eccentric and strap for oscillating 10 said jaws inwardly at their points of contact during a material part of a revolution of the carrier after a sheet has been gripped by the jaws, and for thereafter oscillating the jaws in the opposite direction to eject 15 the folded sheet, and means for turning said eccentric while the machine is running for the purpose of adjusting the jaws relative to each other.

6. The combination of a rotary carrier, a pair of sets of oscillatable jaws mounted on said carrier, an eccentric on the shaft of the carrier, an eccentric strap carried by the carrier, means operated by said eccentric and strap for oscillating said jaws inwardly at 25 their points of contact during a material part of a revolution of the carrier after a sheet has been gripped by the jaws, and for thereafter oscillating the jaws in the opposite direction to eject the folded sheet, the 30 jaws of each set being fixed with respect to each other, and yielding means for moving the jaws of one set toward the other set of jaws for the purpose of providing tension.

7. The combination of a rotary carrier, a pair of parallel shafts, a set of oscillatable jaws mounted on each shaft, means for oscillating said shafts, the jaws of each set being fixed with respect to each other, and yielding 40 means for moving one of the shafts toward the other and bodily moving one set of jaws for providing tension.

8. In a folding delivery mechanism, the combination of a folding cylinder, a rotary carrier having means for receiving folded sheets from the cylinder and gripping them at the fold, a single bending roller at substantially equal distances from the folding cylinder and carrier for supporting one loose end of the folded sheet as it moves 50 away from the folding cylinder, and means for positively driving the bending roller.

9. In a folding delivery mechanism, the combination of a folding cylinder for receiving a web, a rotary carrier directly below it having means for receiving folded sheets therefrom, and gripping them at the fold, a bending roller at a point substantially in horizontal alignment with the point of contact of the folding cylinder and car-

rier for supporting the loose end of the folded sheet as it is being moved away from the folding cylinder, and means for driving the bending roller at web speed, said carrier being at the bottom.

10. The combination of a rotary carrier, a shaft therefor, a pair of discs near the ends of said shaft, gripping members supported by said discs for receiving the fold of a sheet from a tucker blade or the like, strippers arranged for stripping the sheets from the carrier, movable stops adjustably mounted on the strippers, and delivery mechanism for receiving the sheets from the carrier.

11. The combination of a rotary carrier, a shaft therefor, a pair of discs near the ends of said shaft, gripping members supported by said discs and extending from one to the other for receiving the fold of a sheet from a tucker blade or the like, a series of circular supports mounted on said shaft between said discs and spaced apart for supporting the sheets as they pass around with the carrier, strippers arranged for stripping the sheets from the carrier, movable stops adjustably mounted on the strippers, and delivery mechanism for receiving the sheets from the carrier.

12. In a folding delivery mechanism, the combination with a folding cylinder having a tucker blade, of a rotary carrier having means for receiving sheets from the folding cylinder, gripping them at the fold and drawing the fold inward toward the center of the carrier as the carrier rotates through a material part of a revolution, a bending roller at a point adjacent to the folding cylinder and carrier for supporting the loose end of the folded sheet as it is being moved away from the folding cylinder, and means for positively driving the bending roller at web speed.

13. In a folding delivery mechanism, the combination of a folding cylinder, a rotary carrier having means for receiving folded sheets and gripping them at the fold, a bending roller at a point adjacent to the folding cylinder and carrier for supporting the loose end of the folded sheet as it is being moved away from the folding cylinder, said carrier being arranged to deliver at a point materially beyond said roller, and means for positively driving the bending roller at web speed.

In testimony whereof we have hereunto set our hands, in the presence of two subscribing witnesses.

HENRY A. WISE WOOD.
CONRAD NORDFORS.
